LOCK

Irving J. Fletcher, New Britain, Conn., assignor
to The American Hardware Corporation, New
Britain, Conn., a corporation of Connecticut

Application December 11, 1939, Serial No. 308,618

11 Claims. (Cl. 70—38)

My invention relates more particularly to the class of locks known as padlocks, although it may not necessarily be confined to such structure, and an object of my invention, among others, is the production of a lock having means for secretly securing the plug or barrel in place so that it may be removed without the use of any particular tool; a further object of the invention is to provide means for securing the plug or barrel and the inner case so that they may be removed by a single locking element but only when the particular manner of removal is known; another object of the invention is to reduce the cost of manufacture of this class of lock by increasing the speed of assembly and reducing the number of parts; and a still further object of the invention is to produce a lock assembly whose parts are secured together in such a manner as to be more secure against discovery of the disassembly action when in the locked position.

One form of a lock embodying my invention and in the construction and use of which the objects herein set out, as well as others, may be attained is illustrated in the accompanying drawing, in which—

Figure 1 is a side view of my improved lock.
Figure 2 is an edge view of the same.

Figure 3 is a bottom view.

Figure 4 is a view in central vertical section 30 on a plane coincident with the plane of the axes of the two branches of the shackle the latter, however, being shown in full.

Figure 5 is a view in cross section on a plane denoted by the dotted line 5—5 of Fig. 4 and showing the retaining key in its locking position.

Figure 6 is a similar view but showing the retaining key in its releasing position.

Figure 7 is a view similar to Fig. 4 but showing the inner case released and partially removed 40 from the outer case or shell.

Figure 8 is an isometric perspective view of the outer and inner cases with the latter in position for insertion into the shell.

Figure 9 is a view on enlarged scale of a fragment 45 of the lock showing the retaining key in position for securing the plug or barrel and the case within the shell.

Figure 10 is a similar view illustrating the releasing position of the retaining key.

50 In the accompanying drawing the numeral 12 denotes the outer case or shell, which will be hereinafter referred to as the shell, as constructed for use as a padlock, and 13 denotes the inner case thereof which is formed to nicely fit 55 within the shell to be housed therein, and which

is secured in a manner to be hereinafter described. The usual shackle common to such locks has a long arm 14 secured within the structure and a shorter arm 15, both of said arms having locking notches to receive locking bolts 16 which are spring pressed apart to engage said notches, as shown in Fig. 4. The shackle is held in place in a socket partially formed in the outer shell and the inner case, and by means of a pin 17 engaged within an annular groove in the long arm 14, as shown in Figs. 4 and 5. The locking bolts are operated by means of pins 18 projecting from the end of the plug or barrel 19, rotation of which is controlled by key operated pins or tumblers in a manner common to locks of this type. All of the parts thus far described, except as to details of construction, are old and well known in the art and further description is therefore omitted. The pin tumblers are not shown, but their location and operation will be readily understood by those skilled in the art, recesses 20 in the inner case to receive said pin tumblers only being shown.

My invention relates more particularly to means for securing the inner case within the outer shell and also for securing the plug or barrel within the inner case, such means being constructed and arranged to cause automatic fastening of said members in place but to require special knowledge for release of the fastening 30 means which may be effected without the use of particular tools. In carrying out my purpose the outer shell is provided on its interior at one edge with a locking recess 21 formed with a locking shoulder 22 and a cam 23 leading up to said recess, as shown in Figs. 7 and 8. The plug or barrel 19 is likewise provided with a retaining recess 24, said recess and the recess 21 in the outer shell being located, when the plug is in its operative position, opposite each other and also in position to receive opposite ends of a retaining key 25. This retaining key is carried in a hole 26 extending from one edge of the inner case 13 into the hole therein for the barrel or plug 19. The inner end of this retaining key is of particular 45 shape which consists of a plug retaining lip 27 at one edge of said end and an abutment 28 at the opposite edge thereof. The retaining recess 24 is also of angular shape, being provided with a shoulder 29 at one end of the recess which recess decreases in depth from said shoulder to the opposite end where it terminates in a stop 30 at the surface of the plug. The retaining key 25 has an opening to receive a spring 31, the hole 26 being counterbored to receive said spring and 50

the latter resting upon the shoulders created by said counterbore.

When the parts are in the positions shown in Figs. 5 and 9 the plug or barrel may be turned 5 in one direction to effect release of the shackle, the rotation of the barrel in opposite directions being limited by engagement of the locking bolts 16 in the notches in the long and short arm of the shackle and by the abutting of the locking 10 bolts against each other, this being common to locks at the present time. In this locking and unlocking rotation of the plug or barrel the retaining lip 21 is always located in the retaining recess 24 so that said plug is retained in place. 15 When it is desired to disassemble the parts the key is inserted in the barrel and the latter is turned to the right when looking at the bottom end of the lock and until it reaches a stop which is the position shown in Fig. 6. This operation 20 releases the shackle which automatically moves outwardly releasing the short arm from the hole in the case. This short arm may now be swung to one side, incidently opening said hole for free access to the end of the retaining key 25 which 25 may, by insertion of a sharp instrument into said hole, be forced backwardly, the recess 24 being in position to permit such movement. The retaining key is thus released from the recess 21, and the inner case 13 is free to be removed from 30 the shell, and then by pulling the retaining key outwardly the barrel 19 is released for removal from the inner case.

To assemble the parts the operation is reversed, the regular lock key being employed to turn the 35 barrel to locate the retaining recess 24 in the position shown in Fig. 6. The inner case now being pushed into the shell the outer end of the retaining key 25 rides along the cam 23 until it passes the shoulder 22 when the spring 31 forces 40 it into the recess 21.

The shoulder 22 is inclined upwardly from its outer to its inner edge toward the shackle end of the case, and after inserting the inner case within the shell, the end of the retaining key having 45 passed the shoulder 22, the regular lock key may be employed to turn the barrel to its locking position. The cam shaped bottom of the recess engaging the end of the retaining key will force the end of said key up the incline of the shoulder 50 22 and thereby draw the parts inwardly to tight engagement within the case.

It will now be seen that the lock may be operated for locking and un'locking in the usual way and the manner of disengaging the parts will not 55 be readily detected. Any effort to manipulate the retaining key by insertion of an element into the hole for the short arm of the shackle will be ineffectual unless the plug be turned to the proper position, and this would not be readily discovered for the reason that the normal position of the plug is the locking position for the lock. The plug is yieldingly retained in this 60 position by the pressure of a locking bolt spring 32 and it would not be readily discovered that the plug must be held in unlocking position 65 against the pressure of said spring in order to enable the retaining key 25 to be released in the manner above described.

In accordance with the provisions of the patent 70 statutes I have described the principles of operation of my invention, together with the device which I now consider to represent the best embodiment thereof; but I desire to have it understood that the device shown is only illustrative 75 and that the invention may be carried out by

other means and applied to uses other than those above set out.

I claim:

1. A lock including an outer shell having an opening for the short arm of a shackle and a locking recess accessible through said opening, an inner case insertable into said shell and having a hole for a retaining key, said hole opening into a hole for a key plug, a retaining key located in said hole therefor in position to enter said recess, and a key plug located in said hole therefor and having a releasing recess positioned to receive one end of said retaining key to permit its disengagement from said locking recess.

2. A lock including an outer shell having an opening for the short arm of a shackle and a locking recess accessible through said opening, an inner case insertable into said shell and having a hole for a retaining key, said hole opening into a hole for a key plug, a retaining key located in said hole therefor in position to enter said locking recess, a key plug located in said hole therefor and having a releasing recess positioned to receive one end of said retaining key to permit its disengagement from said recess, and means for yieldingly holding said key plug in position to prevent entrance of said retaining key into the recess therein.

3. A lock including an outer shell having an opening for the short arm of a shackle and a locking recess accessible through said opening, an inner case insertable into said shell and having a hole for a retaining key, said hole opening into a hole for a key plug, a retaining key located in said hole therefor in position to enter said locking recess, a key plug located in said hole therefor and having a releasing recess positioned to receive one end of said retaining key to permit its disengagement from said locking recess when the key plug is turned from its locking position, 40 said recess rejecting said retaining key when the plug is in its locking position, and means for automatically returning the key plug to its locking position.

4. A lock including an outer shell having an opening for the short arm of a shackle and a locking recess accessible through said opening, an inner case insertable into said shell and having a hole for a retaining key, said hole opening into a hole for a key plug, a retaining key located in said hole therefor in position to enter said locking recess, a cam engageable with said retaining key to force it into said hole therefor and shaped to release said key when the inner case is fully inserted in the outer shell, and a key plug located in said hole therefor and having a releasing recess positioned to receive one end of said retaining key to permit its disengagement from said locking recess.

5. A lock including an outer shell having an opening for the short arm of a shackle and a locking recess accessible through said opening, an inner case insertable into said shell and having a hole for a retaining key, said hole opening into a hole for a key plug, a retaining key located in said hole therefor in position to enter said locking recess, a key plug located in said hole therefor and having a releasing recess positioned to receive one end of said retaining key to permit its disengagement from said locking recess, only when said key plug is turned from its locking position, and a cam located on the outer shell and engageable with the outer end of said retaining key to force it into the releasing recess.

in the key plug when the latter is turned from its locking position.

6. A lock including an outer shell having an opening for the short arm of a shackle and a locking recess accessible through said opening, said recess having an inclined shoulder, an inner case insertable into said shell and having a hole for a retaining key, said hole opening into a hole for a key plug, a retaining key located in said hole therefor in position to enter said locking recess and engageable with said inclined shoulder to draw the inner case into the outer shell when forced into said recess, and a key plug located in said hole therefor and having a releasing recess positioned to receive one end of said retaining key to permit its disengagement from said locking recess, said releasing recess having a formation to engage the inner end of said retaining key and force it into said locking recess when the key plug is turned to a certain position.

7. A lock including an outer shell having an opening for the short arm of a shackle and a locking recess accessible through said opening, an inner case insertable into said shell and having a hole for a retaining key, said hole opening into a hole for a key plug, a retaining key located in said hole therefor in position to enter said locking recess, a key plug located in said hole therefor and having a releasing recess positioned to receive one end of said retaining key to permit its disengagement from said locking recess, said key plug having a formation to engage the inner end of said retaining key and prevent its inward movement when the key plug is in a certain position.

8. A lock including an outer shell having an opening for the short arm of a shackle and a locking recess accessible through said opening, an inner case insertable into said shell and having a hole for a retaining key, said hole opening into a hole for a key plug, a retaining key located in said hole therefor in position to enter said locking recess, and a key plug located in said hole therefor and having a releasing recess positioned to receive one end of said retaining key to permit its disengagement from said locking recess, said releasing recess having a formation to engage the inner end of said retaining key and force it into said locking recess when the key plug is turned to a certain position.

to force said retaining key against the bottom of said locking recess, said plug also having a formation to prevent inward movement of said retaining key when the key plug is in a certain position.

9. A lock including an outer shell having an opening for the short arm of a shackle and a locking recess accessible through said opening, an inner case insertable into said shell and having a hole for a retaining key, said hole opening into a hole for a key plug, a retaining key located in said hole therefor in position to enter said locking recess, a key plug located in said hole therefor and having a releasing recess positioned to receive one end of said retaining key to permit its disengagement from said locking recess, and a lip on the inner end of said retaining key constantly engaged in said releasing recess to hold the key plug in place when the inner case is secured within the outer shell.

10. A lock including an outer shell having an opening for the short arm of a shackle and a locking recess accessible through said opening, an inner case insertable into said shell and having a hole for a retaining key, said hole opening into a hole for a key plug, a retaining key located in said hole therefor in position to enter said locking recess, a key plug located in said hole therefor and having a releasing recess positioned to receive one end of said retaining key to permit its disengagement from said locking recess, and interengaging means on said plug and retaining key for locking the key plug within the inner case when the latter is secured within said shell.

11. A lock including an outer shell having an opening for the short arm of a shackle and a recess accessible in said opening, an inner case insertable into said shell and having a hole for a retaining key, a retaining key located in said hole and movable into said recess, lock mechanism including a key plug, and means operative by said key plug to move said retaining key into said recess and to permit its removal therefrom to secure and release said inner case.

IRVING J. FLETCHER.
